UNITED STATES PATENT OFFICE.

IVOR D. THOMAS, OF PALMYRA, OHIO, ASSIGNOR TO THE WELLMAN SEAVIER MORGAN COMPANY, OF CLEVELAND, OHIO, A CORPORATION OF OHIO.

BOTTOM-TILTING-DOOR EXTRACTOR.

Application filed April 3, 1925. Serial No. 20,421.

This invention relates to door extractors, and particularly to machines adapted to travel along the front of a battery of coke ovens and provided with means for removing 5 and replacing the doors at the ends of the oven chambers. These doors are very heavy and are held tightly in the door frames by the clay used to seal the space between the edges of the doors and the sides of the door frames. 10 In removing the doors it is necessary to free the doors from their frames and to move them laterally out of the door frames.

The present invention has for an object to provide mechanism capable of engaging 15 and removing the doors quickly and with a minimum expenditure of power.

A further object is to provide means for stripping a door from its casing by a tilting movement such that the weight of the door is 20 automatically transferred to the extractor without lifting the door in such a manner that the extractor may be backed away from the door frame to carry the door to a position clear of its frame.

25 With the above and other objects in view, the invention may be said to comprise a door extracting mechanism as disclosed in the accompanying drawings and hereinafter described and particularly set forth in the appended claims, together with such variations and modifications thereof as will be apparent to one skilled in the art to which the invention appertains.

Reference should be had to the accompanying 30 drawings forming a part of this specification in which the Fig. 1 is a side elevation of the door engaging portion of the door extractor; Fig. 2 is a front elevation of the door engaging portion of the extractor, portions of 40 the casing being shown in section; Fig. 3 is a section of line 3—3 of Fig. 1.

Referring to the accompanying drawings, the door frame in which the door is mounted is indicated by the numeral 1 and the door 45 mounted in the frame by the numeral 2, the door 2 being provided upon the outer side thereof with outwardly projecting brackets 3, adapted to be engaged by the upper and lower door engaging hooks of the extractor. The 50 door extractor mechanism is preferably mounted on a car which travels on a track extending along the front of the ovens. Since

this is the usual manner of mounting door extractors the carriage and track have not been 55 illustrated.

In Fig. 1 of the drawing there is shown a portion of the carriage 4 upon which there is mounted a ram 5 which is adapted to be moved transversely of the carriage toward and from the door openings by means of a pinion 6 operated by suitable driving mechanism on the carriage. Upon the forward end of the ram 5 there is rigidly secured a vertically disposed casing 7 which is open at the front to accommodate the projecting door engaging 60 members and has an enlarged portion 8 at the upper end thereof for housing the operating mechanism.

Adjacent the upper end of the casing there is mounted a pair of L-shaped door engaging 70 members 9 having forwardly projecting door engaging arms 10. The members 9 are suspended from a horizontal pivot pin 11 carried by the side walls of the casing 7 and passing through the upper ends of the members 9, the 75 members 9 being positioned adjacent the opposite side walls of the casing 7. The members 9 are rigidly connected and provided with a buffer spring 12 interposed between the members 9 and the rear wall of the casing 7, 80 the spring 12 permitting the members 9 to swing rearwardly when the door engaging arms 10 are engaged with the door. The upper door engaging hook 13 is pivoted between the arms 10 upon a horizontal pin 14 connecting the L-shaped members 9 adjacent the bend thereof and the hook 13 is provided with an upwardly extended integral arm 15 by means of which it may be swung about the pivot 14 into engagement with the upper 85 bracket 3 on a door.

A lever 16 is mounted within the casing 7 upon horizontal pivot pin 17 toward the lower end of the casing and the lever 16 projects below pivot pin 17 and has a lower forked end 18 extending forwardly toward the door. The forked end 18 of the lever 16 extends forwardly from the casing 7 and substantially the same distance as the arms 10 of the upper 95 yieldably mounted members 9 and the outward movement of the lower end portion of the lever 16 is cushioned by a buffer spring 19 interposed between the lever 16 and the rear wall of the casing 7, the outward movement of 100

the lower end of the lever 16 being limited by an abutment 20 on the rear wall of the casing 7. A lower door engaging hook 21 lies between the spaced arms 18 at the lower end of the lever 16, being pivoted on a horizontal pivot pin 22 extending between the arms 18. The lower door engaging hook 21 is of substantially the same length as the upper hook 13 and is connected thereto by means of a link 10 23 which causes the hook 21 to be moved simultaneously with the hook 13 into door engaging position, the links 23 being preferably adjusted to a length such that the hook 13 engages its bracket first and exerts the upward 15 thrust on the door.

For operating the door engaging hooks to strip the door from its frame suitable mechanism is provided at the upper end of the casing 7. An electric motor 24 is mounted 20 on the top of the casing and the shaft of the motor is provided with a pinion 25 which meshes with a large gear 26 fixed to a screw 27 which extends horizontally through the enlarged portion 8 of the casing, the screw 25 27 being disposed substantially at right angles to the plane of a door. Mounted upon the screw 27 there is a nut 28 which is held against rotation and caused to travel longitudinally of the screw 27 when the screw is rotated by 30 the motor. Pivotedly suspended from the nut 28 there is a lever 29 which is connected at its upper end to the nut 28. Between the ends thereof, the lever 29 has connected thereto a link 30 which is connected to the lever 35 by means of pivot pin 31 and at its opposite end is provided with a longitudinal slot 32 which receives a pin 33 fixed to the upper end of the arm 15 of the upper door engaging hook. The lower end of the lever 29 is connected by a link 34 with the upper end of the lever 16, the link 34 being pivoted at one end at 35 to the lever 29 and at its opposite end at 36 to the upper end of the lever 16. When the nut 28 is at the forward end of the screw 27, the lever 29 will be held in a position such that the door engaging hooks 13 and 21 are in their lowermost positions indicated in dotted lines in Fig. 1. If the motor 24 is operated in a direction to cause the nut 28 40 to travel rearwardly on the screw 27 the link 30 will be drawn rearwardly causing the hooks 13 and 21 to move upwardly, the lever 29 first moving about the pivot 35 as a fulcrum since the forward thrust on the upper 45 end of the arm 16 is insufficient to move the arm 16 in opposition to the buffer spring 19.

In extracting the door from its frame the ram 5 is actuated toward the door until the engaging arms 10 and 18 are brought into 50 contact with the outer face of the door, the arms 10 and 18 serving to properly position hooks 13 and 21 with respect to brackets 3 on the door so that when the hooks 13 and 21 are swung upwardly by the actuating mechanism as above described they will engage

with the brackets 3. As soon as the hooks 13 and 21 have been moved by the lever 29 into engagement with the brackets 3 further movement of the lever 29 will cause the hook 13 to exert an upward thrust upon the door, thus imposing a greater load upon the pivot 31 of the lever causing the lever to exert correspondingly greater thrust through the link 34 upon the upper end of the lever 16, causing the lever to exert an outward pull upon the lower door engaging hook 21. The leverage is such that as soon as the hook 13 engages the brackets 3, the upward movement of the hook is stopped and the pivot 31 of the lever 29 becomes the fulcrum, the lower end of the lever swinging forwardly toward the door and moving the lever 16 about its pivot so that the lower door engaging hook 21 is pulled bodily away from the door frame carrying the lower end of the door with it. This movement results in the tilting of the door about an axis toward the upper end thereof which results in the freeing of the door from its casing. As soon as the lower end of the lever 16 strikes the abutment 20, the lever 16 can have no further movement and the actuating lever 29 fulcrums about its lower pivot 35. The lever 29 now moves the upper end of the arm 15 of the hook 13 outwardly and the weight of the door reacts through the hook 13 and pivot upon the pivotally suspended door engaging members 9 carrying the hook, causing the same to swing outwardly about the pivots until the spring 12 is compressed sufficiently to resist the thrust thereon, after which any further movement of the lever 29 causes the hooks 13 to swing upwardly about their pivots lifting the door. The stripping of the door from its casing by pulling the bottom thereof outwardly results in automatically transferring the weight of the door to the door engaging hooks so that the ram 5 may be backed away to carry the door from its casing without further actuation of the door engaging hooks.

Having described my invention, I claim:

1. A door extracting mechanism comprising a support adapted to be positioned in front of a door to be extracted and to be moved toward and from the door opening, upper and lower door engaging hooks carried by the support, the lower hook being movable bodily on the support toward and from the door opening, and means for moving the hooks into door engaging position and for shifting the lower of the hooks outwardly in advance of the upper hook to tilt the door.

2. A door extracting mechanism comprising a support adapted to be positioned in front of a door to be extracted, upper and lower door engaging hooks carried by the support, the lower hook being movable bodily on the support toward and from the door opening, an actuating device, and means connecting said actuating device to said hooks

for simultaneously moving said hooks into door engaging position, and means connecting said actuating device to the lower of said hooks for shifting the same outwardly to tilt the door.

3. A door extracting mechanism comprising a support adapted to be positioned in front of a door to be extracted and to be moved toward and from the door opening, upper and lower door engaging hooks carried by the support, the lower of said hooks being mounted for movement on said support bodily in a direction away from the door, and actuating means for said hooks for moving them to door engaging position, said actuating means having a connection with the lower hook for shifting the same outwardly to tilt the door.

4. A door extracting mechanism comprising a support adapted to be positioned in front of a door to be extracted, upper and lower members carried by said support and mounted for independent movements on the support toward and from the door frames, door engaging hooks pivotally mounted on said members, and means for moving the hooks simultaneously about their pivots into door engaging position and for shifting the lower hook carrying member outwardly to tilt the door.

5. A door extracting mechanism comprising a support adapted to be positioned in front of a door to be extracted, upper and lower door engaging hooks movably mounted on the support, the lower of the hooks being engageable with the door toward the lower end thereof and mounted for movement into door engaging position and for bodily movement outwardly from the door opening, and means for simultaneously actuating said hooks to engage the same with the door, said actuating means having a connection with the lower of the hooks for shifting the same outwardly to tilt the door.

6. A door extracting mechanism comprising a support adapted to be positioned in front of a door, an upper door engaging hook carried by said support and mounted for movement about a horizontal axis, a lever pivoted to the support below the upper hook, a lower door engaging hook connected to said lever by a horizontal pivot, a link connecting the two hooks, means for simultaneously shifting said hooks into door engaging position and for actuating said lever to pull the lower hook outwardly.

7. A door extracting mechanism comprising a support adapted to be positioned in front of a door, an upper door engaging hook carried by said support and mounted for movement about a horizontal axis, a lever pivoted to the support below the upper hook, a lower door engaging hook connected to said lever by a horizontal pivot, a link connecting the two hooks, an actuating lever, and links

connecting said actuating lever to the upper door engaging hook and to the first mentioned lever.

8. A door extracting mechanism comprising a support adapted to be positioned in front of a door, an upper door engaging hook carried by said support and mounted for movement about a horizontal axis, a lever pivoted intermediate its ends to the support below the upper hook, a lower door engaging hook pivoted to the lever below the pivot thereof, a link connecting the upper and lower hooks, and actuating means connected to the upper hook and to the upper end of said lever.

9. A door extracting mechanism comprising a support adapted to be positioned in front of a door, an upper door engaging hook carried by said support and mounted for movement about a horizontal axis, a lever pivoted intermediate its ends to the support below the upper hook, a lower door engaging hook pivoted to the lever below the pivot thereof, a link connecting the upper and lower hooks, an actuating lever, a link connecting said lever to the upper hook, and a link connecting said lever to the upper end of the first mentioned lever.

10. A door extracting mechanism comprising a support adapted to be positioned in front of a door, an upper door engaging hook carried by said support and mounted for movement about a horizontal axis, a lever pivoted intermediate its ends to the support below the upper hook, a lower door engaging hook pivoted to the lever below the pivot thereof, a link connecting the upper and lower hooks, a screw on said support, a nut on the screw, an actuating lever pivotally secured to the nut, a link connecting said actuating lever to the upper hook, a link connecting said actuating lever to the upper end of the first mentioned lever, and means for rotating the screw to shift said nut.

11. A door extracting mechanism comprising a support adapted to be positioned in front of a door, an upper door engaging hook carried by said support and mounted for movement about a horizontal axis, a lever pivoted intermediate its ends to the support below the upper hook, a lower door engaging hook pivoted to the lever below the pivot thereof, a link connecting the upper and lower hooks, an actuating lever, a link connected to said actuating lever intermediate the ends thereof and to the upper hook, a link connecting the lower end of the actuating lever to the upper end of the first mentioned lever, and means connected to the upper end of the actuating lever for operating the same.

12. A door extracting mechanism comprising a support adapted to be positioned in front of a door, a member connected to said support by a horizontal pivot, said member having a forwardly projecting door engaging

part below the pivot, a spring interposed between said member and support; a door engaging hook supported on said member below the pivot thereof by a horizontal pivot, a lever pivoted intermediate its ends to the support below said member, a spring interposed between the lever and support below the pivot of the lever, a lower door engaging hook connected to the lever below the pivot thereof by a horizontal pivot, a link connecting the upper and lower hooks, and means connected to one of the hooks and to said lever for actuating the same to swing the hooks into door engaging position and to move the lower of the hooks outwardly to tilt the door.

13. A door extracting mechanism comprising a support adapted to be positioned in front of a door, a member connected to said support by a horizontal pivot, said member having a forwardly projecting door engaging part below the pivot, a spring interposed between said member and support, a door engaging hook supported on said member below the pivot thereof, by a horizontal pivot, a lever pivoted intermediate its ends to the support below said member, a spring interposed between the lever and support below the pivot of the lever, a lower door engaging hook connected to the lever below the pivot thereof by a horizontal pivot, a link connecting the upper and lower hooks, an actuating lever, a link connecting said actuating lever to the upper hook, and a link connecting said actuating lever to the first mentioned lever.

14. A door extracting mechanism comprising a support adapted to be positioned in front of a door, a member connected to said support by a horizontal pivot, said member having a forwardly projecting door engaging part below the pivot, a spring interposed between said member and support, a door engaging hook supported on said member below the pivot thereof by a horizontal pivot, a lever pivoted intermediate its ends to the support below said member, a spring interposed between the lever and support below the pivot of the lever, a lower door engaging hook connected to the lever below the pivot thereof by a horizontal pivot, a link connect-

ing the upper and lower hooks, an actuating lever, a shiftable supporting member on which said actuating lever is supported, a link having a connection at one end to the hook and at the other end to the lever intermediate its ends, one of said connections being a pin and slot connection, and a link connecting the lever end of the actuating lever to the first mentioned lever.

15. A door extracting mechanism comprising a support adapted to be positioned in front of a door to be extracted, a lever connected to said support by a horizontal pivot, a vertically swinging door engaging hook carried by the lever and an actuating lever having separate connections to the hook and to the first mentioned lever.

16. A door extracting mechanism comprising a support adapted to be positioned in front of a door to be extracted, a lever connected intermediate its ends to the support by a horizontal pivot, a vertically swinging door engaging hook carried by the lever adjacent one end thereof, an actuating lever and thrust transmitting members connected by pivots at spaced points to said actuating lever, said members being operatively connected to said hook and first mentioned lever and said lever being adapted to fulcrum about the pivot of the member offering the greatest resistance to movement.

17. A door extracting mechanism comprising a support adapted to be positioned in front of a door to be extracted, a door engaging member mounted upon the support for movement in an upward direction to lift the door and for movement in an outward direction to tilt the same, a lever connected to said engaging member for exerting an outward thrust thereon, a lever connected to said engaging member for actuating the same in a direction to exert an upward thrust upon the door, said last mentioned lever being connected with the first mentioned lever to actuate the same.

In testimony whereof, I hereunto affix my signature.

IVOR D. THOMAS
